UNITED STATES PATENT OFFICE

ROBERT C. DANLY, OF CHICAGO, ILLINOIS, ASSIGNOR TO DANLY MACHINE SPECIALTIES, INC., OF CHICAGO, ILLINOIS, A CORPORATION OF ILLINOIS

FEEDING MECHANISM

Application filed February 1, 1930, Serial No. 425,173. Renewed September 3, 1931.

This invention relates to certain improvements in the type of automatic feeding appliances by means of which an unfinished valve tappet, or like piece of work, is fed into the grinding throat of a centerless grinding mechanism, an example of which is shown in the George I. Danly Patent No. 1,725,444, dated August 22, 1929. And the present improvement has as its object:—

To provide a simple, durable and efficient structural formation and combination of parts and mechanisms by means of which pieces of unfinished work are serially manipulated and carried from a holding track and deposited in proper position in the grinding throat or zone of a centerless grinding mechanism, with the different manipulating and carrying movements of the present appliance constituting a single cycle of the movements which are set in motion by a starting connection between the work ejecting means of an associated centerless grinding mechanism and the operating mechanism of the present feeding appliance, with such cycle of movements beginning with the deposit of a piece of unfinished work in the grinding throat of said grinding mechanism, and ending with a transfer of a succeeding piece of work into a position ready to be deposited in said grinding throat, all as will hereinafter more fully appear.

In the accompanying drawings:—

Fig. 1 is a side elevation illustrating the general arrangement of parts in a preferred form of the invention.

Fig. 2 is a horizontal section on line 2.—2. Fig. 3, of the mechanism for effecting the intermittent cycle of movements of the machine.

Fig. 4 is a detail vertical section of same on line 3.—3. Fig. 2.

Fig. 5 is a detail side elevation of the same. Fig. 6 is an enlarged detail plan view of the mechanism with the parts in position for engagement with a succeeding piece of work.

Fig. 7 is an enlarged side elevation of same

with parts broken away and in section on line 7.—7. Fig. 6.

Fig. 8 is a fragmentary sectional elevation, showing the work grasping jaws of the carrier in position to deposit a piece of work to be finished in the grinding throat of a centerless grinding mechanism.

Fig. 9 is a detail sectional plan view on line 9.—9. Fig. 8 of the same in the disengaged condition of the grasping jaws and their operating means.

Fig. 10 is a companion view showing said parts in the engaged or grasping condition of the jaws.

Like reference numerals indicate like parts in the several views.

As in the before mentioned Patent No. 1,725,444, this automatic work feeding mechanism or attachment for centerless grinding mechanisms, comprises a supporting frame or base 1, preferably of the shell type shown, and in which is carried an operating mechanism by which the intermittent cycles of operations of the different automatic feeding means and mechanisms of this improvement are serially effected.

The starting of such operating mechanism is effected by an operative connection between the same and the automatic work ejecting mechanism of an associated centerless grinding mechanism. The stoppage of said operating mechanism is attained by self contained means on the completion of one cycle of movements of the automatic feeding means and mechanisms above referred to, and in condition for a succeeding starting operation by the controlling connection with said work ejecting means of the grinding mechanism.

The base 1 of the shell type shown is adapted to contain a motor (not shown) for imparting rotation to automatic operating mechanism aforesaid, and carries a fixed horizontal frame or bracket extension 2 for the support of the hereinafter described parts and mechanisms of this improvement. And in adjacent relation to said bracket extension 2, the base 1 is provided with a fixed lug or ear 3, constituting a part of a coupling means whereby the present feeding attachment is fixedly attached to the frame of a center-

less grinding mechanism, in proper relation to the grinding throat or zone thereof.

On the upper part of the base 1, a holding hopper 4 for a supply of unfinished tappets 5 or the like to be operated on, is fixedly supported, and such hopper is provided with an oscillatory selector plate or member 5 adapted to lift unfinished pieces of work from the hopper and place the same in serial order on an inclined track 6, down which they will slide by gravity and be singly engaged and fed by the automatic feeding mechanisms hereinafter described in detail.

The construction and arrangement of the selector plate or member 5 is adapted to operate in a manner similar to the selector plate described in the aforesaid Danly Patent No. 1,725,444, and is such that in case headed tappets or the like are to be selected, the same will be selected and placed on the track 6 with their headed portions in rearward positions thereon.

Adjacent to the mid-length of the track 6 a revolute disk 7 is arranged, and provided with a series of radial blades 7' on its perimeter, the blades being adapted to engage the pieces of work moving down the inclined track 6 and retard an undue rapidity of descent of the pieces of work and insure a further descent of each piece in a single and successive order. Rotation of the disk 7 is attained by operative connection thereof with a suitable power source, preferably the means set forth in my application for Patent Serial No. 425,172, filed February 1, 1930.

In adjacent and offset relation to the lower end of the track 6, a receiving downspout or boot 8 is fixedly supported on the base 1, and a transfer means is located between the lower end of the track 6 and the upper and receiving end of the downspout 8, with said transfer means involving a construction and arrangement as follows:

A fixed guide frame 9 is arranged between the lower end of the track 6 and the upper end of the downspout 8, to provide a guide-way for a transversely reciprocating slide or carrier 10, formed with a receiving notch or recess 10' for the reception of and engagement with the shank portion of a piece of work lowermost on the track 6.

With the movement of the slide or carrier 10 in one direction the piece of work in the notch 10' will be carried from the lower end of the track 6 to a point over the downspout 8 into which it is discharged by a knock out blade 11 pivoted at 11' on the guide frame 9 and provided with a projecting lug 12, with which an adjustable stem or

tappet 13 on the slide 10 has operative contact as said slide or carrier nears the end of its stroke towards the downspout, to effect a movement of the blade 11 and discharge the piece of work from the notch 10' into the downspout 8.

Reciprocation of the slide or carrier 10 is attained at proper intervals by means of a rock arm 14 on a rock shaft 14' that has angle gear connection with a horizontal shaft 15, which in turn carries a rock arm 15' the free end of which is arranged in the path of an operating tappet 16 carried on the hereinafter described carrier frame or bar 22 of the automatic feeding means by which pieces of unfinished work are picked up, carried and serially deposited in the grinding throat of an associated grinding mechanism.

Mounted on the frame extension 2 of the main base 1 and in receiving relation with the downspout 8, is an endless carrier 17 the end carrying sheaves 17' of which are journaled on said frame extension 2.

The upper stretch of the endless carrier 17 has preferably a downward inclination as shown, with a view to an easy transfer of pieces of work to the next unit of the present feeding mechanism. While the travel of the endless carrier 17 is preferably attained by a shaft connection 18 of the universal type forming the operative connection between a carrying sheave 17' of said carrier and a convenient power shaft.

In adjacent relation to the delivery end of the endless carrier 17, a horizontal trough shaped receiving platform 19 is movably mounted on the aforesaid frame extension 2 by a plurality of radius links 20, so as to be capable of limited vertical movement in actual use. The platform 19 is adapted to receive from the aforesaid endless carrier 17, a piece of unfinished work, such as the headed tappet shown, which is properly positioned in the platform by stop abutment of the head of the tappet against the end of the same, as illustrated in Figs. 6 and 7.

In the construction shown, the piece of unfinished work in the vale of the platform 19 is carried and deposited between the grinding wheel 21 and feeding wheel 21' of an associated centerless grinding mechanism by means as follows:

A carrier 22, of the elongated bar type shown, is arranged in operative relation to the receiving platform 19 aforesaid, and receives longitudinal reciprocation towards and from the grinding throat of the grinding mechanism above referred to, by operative connection to one end of a rock arm 23, forming a part of an automatic driving and control mechanism hereinafter described, and at its other end the carrier 22 is carried a pair of work grasping jaws 22', 22" preferably of the detail construction hereinafter described.

The under face of said carrier or bar 22, has sliding support intermediate its length on a bearing roller 24 journaled on the extension or bracket 2 of the main base 1. And with a view to a limited rising and falling movement of the jaw carrying end of the carrier or bar 22, in the actual operation of the mecha-

nism, said carrier or bar has a formation on its under side as follows:—

The under or bearing face of the carrier or bar 22 is formed with inclined portions 25 and 26 in longitudinal spaced relation, and connected together by an intermediate slightly inclined portion 27. With such formation, in a movement of the aforesaid inclined portion 25 upon the bearing roller 24 in the initial movement of the carrier towards the aforesaid grinding mechanism, an upward swinging movement of the carrier and its grasping jaws 22', 22' is attained, and the upward position thus attained is maintained by the aforesaid intermediate portion 27, while a downward swinging motion of the carrier and its grasping jaws 22', 22' as the same nears the end of the described forward movement is attained by a riding of the inclined portion 26 down the bearing roller 24.

The movement and operations above described, take place in the forward or feeding stroke or movement of the carrier 22, while in an opposite or return movement or stroke of said carrier, the movements and operations which take place are as follows:

With its inclined portion 25 of the carrier riding up on the bearing roller 24 in a forward stroke of the carrier, the carrier receives an upward swinging movement which is maintained by the intermediate portion 27 of the carrier riding along the bearing roller 24, and until the inclined portion 26 aforesaid reaches said bearing roller to ride down on the same, into the secondary lowered condition, with its grasping jaws 22', 22' in the grinding throat of an associated grinding mechanism. In the return stroke of the carrier the reverse of the movements above described takes place.

The work grasping or holding jaws 22', 22' of the carrier 22 aforesaid, comprises a pair of plate metal members yieldingly attached at their upper ends to an end of said carrier, with a normally closed condition of the jaws maintained preferably by a spring 28 acting to yieldingly move said jaws together.

Opening or separating movement of the jaws 22', 22' to receive and to discharge pieces of work is positively attained by a construction and arrangement of parts as follows:—

A release bar 29, of a round or other shape in cross section, is arranged in frictional contact with the carrier 22, preferably in a guide groove in the side of the same, with one end of said release bar 29 adapted for operative engagement with the grasping jaws 22', 22', and in the construction shown said release bar 29 is held against longitudinal movement during the respective periods in which the carrier 22 nears the end of its forward and return travel, and to such end the bar 29 carries lateral lugs 30 for alternate stop engagement with a pair of fixed stop lugs 31 and 31' arranged in properly spaced relation on

the main base 1 and which act to hold in release bar in the stationary conditions above described, so that as said carrier in independent final movements to attain alternate opening and closing movements of the grasping jaws 22', 22', by intermediate means as follows:

The forward end of the release bar 29 is arranged between the respective jaws 22', 22', and is formed with a cam shaped recess 32, which in an assembled condition of the parts has near relation to the middle of the jaws, with the cam recess 32 in operative engagement with one side of a loose member 33, preferably of spherical form shown, which is arranged in a lateral passage in the carrier 22.

The opposite side of the ball or member 33 has operative contact with a yielding jaw of the pair of grasping jaws 22', 22', so that with the described construction, as the ball or member 33 is carried out of the cam recess 32 by an independent movement of the carrier 22 in a direction towards the grinding throat of an associated grinding mechanism, a separation of the grasping jaws is effected with a release of a piece of work held between the same into the grinding throat just mentioned. In such release movement of the parts, the release bar 29 is held stationary by contact with the stop lug 30' on the main frame 1.

In the reverse or return stroke of the carrier 22, the grasping jaws and their operating means retain the opened position above described until near the end of such return stroke of the carrier 22, in which period the release bar 29 by contact with the stationary stop 31' while the carrier 22 in its further travel acts to shift the ball or member 33 into the cam recess 32, and permit the grasping jaws 22', 22' to close into holding engagement with a piece of work held between the jaws by the platform 19 aforesaid.

The presentation of a piece of work between the grasping jaws 22', 22' above referred to, is attained by an upward swing of the platform 19 with its contained piece of work, from its normal position in line with the endless conveyor 17, is effected by a pin or stud 34 on the carrier which by contact with a projection 35 on the platform 19 is adapted to swing said platform in an upward direction on the links 20, heretofore described.

A subsequent descent of the platform 19 to the above mentioned normal position may be attained by gravity of the parts, or by means of a secondary stud on the carrier 22, which by contact with the other side of the aforesaid projection 35 of the platform is adapted to positively effect such descent.

On or about the period in which the operating contact of the stud 34 with the projection 35 is released, the heretofore described stud 16 on the carrier has operative contact with the rock arm 15' of the intermittent operating mechanism of the heretofore de-

scribed transverse slide or carrier 10 to shift the lowermost piece of work from the inclined track 6 into the downspout 8 for delivery of the work onto the endless conveyor 17 and thence to the platform 19 for a succeeding cycle of operations of the feeding mechanism above described.

The automatic controlling means for effecting the operations of the different mechanisms of the present construction in proper and successive order, is similar to that described and claimed in another application for patent Serial No. 425,172, filed February 1, 1930, and comprises a construction and arrangement of parts as follows:

An endless screw shaft 36 is journalled longitudinally in the main base 1 and receives constant rotation through a pulley and belt connection to the power shaft of a motor which may be located within the main base 1. The endless screw or worm part of the shaft 36 has operative engagement with a worm wheel 37 on a transversely arranged shaft 38 that has suitable operative connection with the heretofore described bladed disk 7 associated with the inclined track 6 of the structure.

In addition said primary shaft 38 has gearing connection 39 with the carrying hub 40 of the driving element of a clutch 41, with said hub loosely mounted on a secondary shaft 42. The carrying hub 43 of the driven element of the clutch 41 is mounted in a slideable manner on the secondary shaft 42 aforesaid, and in rotatable engagement therewith. The purpose being to attain revolution of the secondary shaft 42 from the primary shaft 38, only during the clutch engagement between the hubs 40 and 43.

In the construction shown, the above referred to intermittent engagement of the hubs 40 and 43, is automatically effected and maintained while a single and complete revolution of the secondary shaft 42 is effected, by means as follows:

The carrying hub 43 of the driven element of the clutch 41 is provided with a cam projection 44, preferably arranged in a peripheral channel in the hub as shown, with such cam projection adapted for operative engagement with an end portion of a locking or abutment bar 45, preferably of the sliding type shown, and so that with an engagement of said cam projection against the end of said bar 45, the carrying hub of the driven clutch element, and of which hub the cam projection is a fixed part, will be positively moved and held out of clutch engagement until a release of the above described engagement between the cam projection 44 and the abutment bar 45, by a movement of said bar 45 out of such engagement by automatic means hereinafter described.

With an attainment of such disengagement, an associated spring 46 operates to

move the driven element of the clutch 41 into clutching engagement with the driving element thereof in the attaining of a succeeding single revolution of the secondary shaft 42 and its accessories.

Automatic withdrawal of the locking or abutment bar 45 from the engaged condition above described, is attained by operative connections of said bar 45 with a reciprocating part of the automatic work ejecting unit of a centerless grinding mechanism, with such connection preferably comprising a pulling link 47 attached at one end to a convenient part of said work ejector unit, and at the other end to a rock arm 48 on a transverse shaft 49 that is journalled on the main base 1, with said shaft 49 carrying a secondary rock arm 50 and link connection 51 with locking or abutment bar 45 aforesaid.

The aforesaid primary shaft 38 carries in an end outside the main base 1, a wiper arm 52 adapted to engage and operate the oscillatory selector plate 5 of the work holding hopper 4.

The secondary shaft 42 aforesaid carries a crank disk 53 the crank pin of which is connected by a link 54 with a crank arm 55 on a transverse rock shaft 56 journalled in the wall of the main base 1. The end of said rock shaft 56 exterior of the base 1 carries the heretofore described rock arm 23, as the means for imparting reciprocation to the work carrier 22, and the construction is such that the rock arm 23 receives a full forward and a full return stroke in each intermittent action of the control mechanism just described.

The operation of the mechanism as a whole, is described in connection with the description of each unit of the present feeding mechanism, and in view of which a description of the serial operation of the parts is not deemed necessary.

Having thus fully described my invention, what I claim as new, is:—

1. In a feeding mechanism of the type described, the combination of a supporting base, a horizontal work holding platform mounted on said base, a single delivery supply means mounted on said base in operative relation to said platform, a reciprocating carrier associated with said mechanisms, and provided with work grasping jaws of the yieldingly held closed type, means for imparting a rising initial movement and a final falling movement to the jaw carrying end of said carrier in its delivery stroke, and corresponding reverse movements on its return stroke, and means for closing the grasping jaws in the return condition of the carrier and for opening said jaws in the delivery condition of the carrier.

2. In a feeding mechanism of the type described, the combination of a supporting base, a work holding platform mounted on said base, a single delivery supply means mounted

- on said base in operative relation to said platform, a reciprocating carrier associated with said mechanisms, and provided with work grasping jaws of the yieldingly held closed type, means for imparting a rising initial movement and a final falling movement to the jaw carrying end of said carrier in its delivery stroke, and corresponding reverse movement on its return stroke, and means for closing the grasping jaws in the return condition of the carrier and for opening said jaws in the delivery condition of the carrier, the same comprising a release bar moving in unison with said carrier with its forward end extending between the grasping jaws and provided with a cam formation adapted for opening engagement with said jaws.
3. In a feeding mechanism of the type described, the combination of a supporting base, a work holding platform mounted on said base, a single delivery supply means mounted on said base in operative relation to said platform, a reciprocating carrier associated with said mechanisms, and provided with work grasping jaws of the yieldingly held closed type, means for imparting a rising initial movement and a final falling movement to the jaw carrying end of said carrier in its delivery stroke, and corresponding reverse movement on its return stroke, and means for closing the grasping jaws in the return condition of the carrier, means for opening said jaws in the delivery condition of the carrier, an automatic control mechanism geared to make a single revolution and having starting connection with the work ejecting mechanism of a centerless grinding mechanism, and a vibratory arm receiving a forward and a backward stroke from said control mechanism and having operative connection with the carrier aforesaid.
4. In a feeding mechanism of the type described, the combination of a supporting base, a work holding platform mounted on said base, a single delivery supply means mounted on said base in operative relation to said platform, a reciprocating carrier associated with said mechanisms, and provided with work grasping jaws of the yieldingly held closed type, means for imparting a rising initial movement and a final falling movement to the jaw carrying end of said carrier in its delivery stroke, and corresponding reverse movement on its return stroke, and means for closing the grasping jaws in the return condition of the carrier and for opening said jaws in the delivery condition of the carrier.
5. In a feeding mechanism of the type described, the combination of a supporting base, a work holding platform mounted on said base, a single delivery supply means mounted on said base in operative relation to said platform, a reciprocating carrier associated with said mechanisms, and provided with work grasping jaws of the yieldingly held closed type, means for imparting a rising initial movement and a final falling movement to the jaw carrying end of said carrier in its delivery stroke, and corresponding reverse movement on its return stroke, and means for closing the grasping jaws in the return condition of the carrier, and for opening said jaws in the delivery condition of the carrier, the same comprising a release bar moving in unison with said carrier with its forward end extending between the grasping jaws, a cam formation on said forward end of the release bar, a member having movement in a transverse passage in the carrier and operative engagement at one side with said cam formation and at the other side with one of the grasping jaws, and a pair of stop members secured in spaced relation on the supporting base and acting to hold said release bar stationary as the carrier completes the end of its forward stroke and the end of its return stroke.
6. In a feeding mechanism of the type described, the combination of a supporting base, a work holding platform mounted on said base, a single delivery supply means carried on said base, an endless carrier arranged intermediate of said platform and supply means, a reciprocating carrier associated with said platform and provided with grasping jaws of the yieldingly held closed type, means for imparting a rising initial movement and a final falling movement to the jaw carrying end of said carrier in its delivery stroke and corresponding reverse movement on a return stroke, and means for closing the grasping jaws in the return condition of the carrier and for opening said jaws in the delivery condition of the carrier.
7. In a feeding mechanism of the type described, the combination of a supporting base, a work holding platform mounted on said base, a single delivery supply means carried on said base, an endless carrier arranged intermediate of said platform and supply means, a reciprocating carrier associated with said platform and provided with grasping jaws of the yieldingly held closed type, means for imparting a rising initial movement and a final falling movement to the jaw carrying end of said carrier in its delivery stroke and corresponding reverse movement on its return stroke, and means for closing the grasping jaws in the return condition of the carrier and for opening said jaws in the delivery condition of the carrier, the same comprising a release bar moving in unison with said carrier with its forward end extending between the grasping jaws, a cam formation on said forward end of the release bar, a member having movement in a transverse passage in the carrier and operative engagement at one side with said cam formation and at the other side with one of the grasping jaws, and a pair of stop members secured in spaced relation on the supporting base and acting to hold said release bar stationary as the carrier completes the end of its forward stroke and the end of its return stroke.

movement on a return stroke, and means for closing the grasping jaws in the return condition of the carrier and for opening said jaws in the delivery condition of the carrier, 5 the same comprising a release bar moving in unison with the carrier with its forward end extending between the grasping jaws and provided with a cam formation adapted for opening engagement with said jaws.

10 8. In a feeding mechanism of the type described, the combination of a supporting base, a work holding platform mounted on said base, a single delivery supply means carried on said base, an endless carrier arranged intermediate of said platform and supply means, a reciprocating carrier associated with said platform and provided with grasping jaws of the yieldingly held closed type, means for imparting a rising initial 15 movement and a final falling movement to the jaw carrying end of said carrier in its delivery stroke and corresponding reverse movement on a return stroke, and means for closing the grasping jaws in the return condition of the carrier and for opening said jaws in the delivery 20 condition of the carrier, an automatic control mechanism geared to make a single revolution and having starting connection with the work ejecting mechanism of a centerless grinding mechanism, and a vibratory arm receiving a forward and a backward stroke from said control mechanism and having operative connection with the carrier aforesaid.

25 9. In a feeding mechanism of the type described, the combination of a supporting base, a work holding platform mounted on said base, a single delivery supply means carried on said base, an endless carrier arranged intermediate of said platform and supply 30 means, a reciprocating carrier associated with said platform and provided with grasping jaws of the yieldingly held closed type, means for imparting a rising initial movement and a final falling movement to the jaw carrying end of said carrier in its delivery stroke and corresponding reverse movement on a return stroke, and means for closing the grasping jaws in the return condition of the carrier and for opening said jaws in the delivery 35 condition of the carrier, the same comprising a release bar moving in unison with the carrier with its forward end extending between the grasping jaws, a cam formation and a pair of stop members carried in spaced relation on the supporting base and

acting to hold said release bar stationary as the carrier completes the end of its forward stroke and the end of its return stroke.

10 10. In a feeding mechanism of the type described, the combination of a supporting base, a work holding platform mounted on said base, a single delivery supply means carried on said base, an endless carrier arranged intermediate of said platform and supply means, a reciprocating carrier associated with said platform and provided with grasping jaws of the yieldingly held closed type, means for imparting a rising initial movement and a final falling movement to the jaw carrying end of said carrier in its delivery stroke and corresponding reverse movements on a return stroke, means for closing the grasping jaws in the return condition of the carrier and for opening said jaws in the delivery condition of the carrier, an automatic control mechanism geared to make a single revolution and having starting connection with the work ejecting mechanism of a centerless grinding mechanism, and a vibratory arm receiving a forward and a backward stroke from said control mechanism and having operative connection with the carrier aforesaid.

11 11. In a feeding mechanism of the type described, the combination of a supporting base, a work holding platform having a rising and falling movement on said base, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in the delivery condition of the carrier.

12 12. In a feeding mechanism of the type described, the combination of a supporting base, a work holding platform having a rising and falling movement on said base, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in the delivery condition of the carrier, the same comprising a release bar moving in unison with said carrier with its forward end extending between the grasping jaws and provided with

a cam formation adapted for operative engagement with said jaws.

13. In a feeding mechanism of the type described, the combination of a supporting base, a work holding platform having a rising and falling movement on said base, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in the delivery condition of the carrier, the same comprising a release bar moving in unison with the carrier with its forward end extending between the grasping jaws, a cam formation on said forward end of the release bar, a member having movement in a transverse passage of the carrier and operative engagement at one side with said cam formation and at the other side with one of the grasping jaws, and means for holding said release bar stationary as the carrier completes the end of its forward stroke and at the end of its return stroke.

14. In a feeding mechanism of the type described, the combination of a supporting base, a work holding platform having a rising and falling movement on said base, a single delivery supply means on said base in operative relation to said platform, a reciprocating carrier associated with said platform, and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in the delivery condition of the carrier, the same comprising a release bar moving in unison with said carrier with its forward end extending between the grasping jaws, a cam formation on said forward end of the release bar, a member having movement in a transverse passage in the carrier and operative engagement at one side with said cam formation and at the other side with one of the grasping jaws, and a pair of stop members secured in spaced relation on the supporting base and acting to hold said release bar stationary as the carrier completes the end of its forward stroke and the end of its return stroke.

15. In a feeding mechanism of the type described, the combination of a supporting base, a work holding platform having a rising and falling movement on said base, a

single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier, means for opening said jaws in the delivery condition of the carrier, an automatic control mechanism geared to make a single revolution and having starting connection with the work ejecting mechanism of a centerless grinding mechanism, and a vibratory arm receiving a forward and a backward stroke from said control mechanism and having operative connection with said carrier.

16. In a feeding mechanism of the type described, the combination of a work holding platform, radius links connecting said platform with the supporting base to afford a rising and falling movement to said platform, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements in its return stroke, and means for closing the grasping jaws in the return condition of the carrier and for opening said jaws in a delivery condition of the carrier.

17. In a feeding mechanism of the type described, the combination of a work holding platform, radius links connecting said platform with the supporting base, to afford a rising and falling movement to said platform, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements in its return stroke, and means for closing the grasping jaws in the return condition of the carrier and for opening said jaws in a delivery condition of the carrier, the same comprising a release bar moving in unison with said carrier with its forward end extending between the grasping jaws and provided with a cam formation adapted for operative engagement with said jaws.

18. In a feeding mechanism of the type described, the combination of a work holding platform, radius links connecting said plat-

- form with the supporting base to afford a rising and falling movement to said platform, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in a delivery condition of the carrier, the same comprising a release bar moving in unison with the carrier with its forward end extending between the grasping jaws, a cam formation on said forward end of the release bar, a member having movement in a transverse passage of the carrier and operative engagement at one side with said cam formation and at the other side with one of the grasping jaws, and means for holding said release bar stationary as the carrier completes the end of its forward stroke and the end of its return stroke. 19. In a feeding mechanism of the type described, the combination of a work holding platform, radius links connecting said platform with the supporting base to afford a rising and falling movement to said platform, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements in its return stroke, and means for closing the grasping jaws in the return condition of the carrier and for opening said jaws in a delivery condition of the carrier, the same comprising a release bar moving in unison with said carrier with its forward end extending between the grasping jaws, a cam formation on said forward end of the release bar, a member having movement in a transverse passage in the carrier and operative engagement at one side with said cam formation and at the other side with one of the grasping jaws, and a pair of stop members secured in spaced relation on the supporting base and acting to hold said release bar stationary as the carrier completes the end of its forward stroke and the end of its return stroke. 20. In a feeding mechanism of the type described, the combination of a work holding platform, radius links connecting said platform with the supporting base to afford a rising and falling movement to said platform, a single delivery supply means on said base in operative relation to said platform, a reciprocating carrier associated with said platform and provided with work grasping jaws of the yieldingly held closed type, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in a delivery condition of the carrier, the same comprising a release bar moving in unison with said carrier with its forward end extending between the grasping jaws, a cam formation on said forward end of the release bar, a member having movement in a transverse passage in the carrier and operative engagement at one side with said cam formation and at the other side with one of the grasping jaws, and a pair of stop members secured in spaced relation on the supporting base and acting to hold said release bar stationary as the carrier completes the end of its forward stroke and the end of its return stroke. 21. In a feeding mechanism, the combination of a supporting base, a work containing hopper provided with a selector mechanism and an inclined track adapted to receive pieces of work from said selector mechanism, a receiving downspout arranged in lateral relation to said track, means for serially transferring pieces of work from the lower end of said track to the downspout, and means for feeding the pieces of work from said downspout into the grinding throat of a grinding mechanism. 22. In a feeding mechanism, the combination of a supporting base, a work containing hopper provided with a selector mechanism and an inclined track adapted to receive pieces of work from said selector mechanism, a receiving downspout arranged in lateral relation to said track, means for serially transferring pieces of work from the lower end of said track to the downspout, and means for feeding the pieces of work from said downspout into the grinding throat of a grinding mechanism, the same comprising a work holding platform in receiving relation to said downspout, a reciprocating carrier associated with said platform and provided at one end with grasping jaws, means for imparting a rising initial movement and a final falling movement to the jaw carrying end of said carrier in its delivery stroke and corresponding reverse movements on its return stroke, and means for closing the grasping jaws in the return condition of the carrier and for opening said jaws in the delivery condition of the carrier. 23. In a feeding mechanism, the combination of a supporting base, a work containing hopper provided with a selector mechanism and an inclined track adapted to receive pieces of work from said selector mechanism, a receiving downspout arranged in lateral relation to said track, means for serially transferring pieces of work from the lower end of said track to the downspout, and means for feeding the pieces of work from said downspout into the grinding throat of a grinding mechanism, the same comprising a work

holding platform, an endless carrier arranged intermediate of said platform and downspout, a reciprocating carrier associated with said platform and provided at one 5 end with grasping jaws, means for imparting a rising initial movement and a final falling movement to the jaw carrying end of the carrier in its delivery stroke, and corresponding reverse movements on its return stroke, and 10 means for closing the grasping jaws in a return condition of the carrier and for opening said jaws in the delivery condition of the carrier.

24. In a feeding mechanism, the combination of a supporting base, a work containing 15 hopper provided with a selector mechanism and an inclined track adapted to receive pieces of work from said selector mechanism, a receiving downspout arranged in lateral relation to said track, means for serially transferring pieces of work from the lower end of 20 said track to the downspout, and means for feeding the pieces of work from said downspout into the grinding throat of a grinding 25 mechanism, the same comprising a work holding platform having a rising and falling movement on said base, a reciprocating carrier associated with said platform and provided with grasping jaws, means for imparting 30 a rising initial movement and a final falling movement to the jaw carrying end of the carrier in its delivery stroke and corresponding reverse movements in its return stroke, and means for closing the grasping jaws in 35 the return condition and for opening said jaws in the delivery condition of the carrier.

25. In a feeding mechanism, the combination of a supporting base, a work containing 40 hopper provided with a selector mechanism and an inclined track adapted to receive pieces of work from said selector mechanism, a receiving downspout arranged in lateral relation to said track, means for serially transferring pieces of work from the lower end of 45 said track to the downspout, and means for feeding the pieces of work from said downspout into the grinding throat of a grinding mechanism, the same comprising a work holding platform, radius links connecting 50 said platform with the supporting base to afford a rising and falling movement to said platform, a reciprocating carrier associated with said platform and provided with grasping jaws at one end, means for imparting a 55 rising initial movement and a final falling movement to the jaw carrying end of said carrier in its delivery stroke and corresponding reverse movements in its return stroke, and means for closing the grasping jaws in 60 the return condition of the carrier and for opening said jaws in a delivery condition of the carrier.

In testimony whereof I hereunto affix my signature.

ROBERT C. DANLY.
